INSIGNIA

Stafford F. Potter, Arlington, Va., assignor to the United States of America as represented by the Secretary of the Army

Filed Dec. 19, 1963, Ser. No. 77,870

Term of patent 14 years

(Cl. D29—2)

(Granted under Title 35, U.S. Code (1952), sec. 266)

FIG. 1

FIG. 2

FIG. 1 is a front elevational view of the insignia.
FIG. 2 is a side elevational view of the insignia shown in FIG. 1.

The rear elevation of my insignia is plain and unornamented.

The essential features of the design reside in the portions shown in solid lines in FIGS. 1 and 2.

The design described herein may be reproduced and used by or for the Government for governmental purposes without the payment to me of any royalty thereon.

I claim:

The ornamental design for an insignia, as shown and described.
